CARTON CLOSING MACHINE

Hugh H. Shaw, Martin I. Sanderson, and Harold G. Bradshaw, Salinas, Calif., assignors to Cochran Equipment Company, Salinas, Calif., a corporation of California

Application January 23, 1956, Serial No. 560,717

7 Claims. (Cl. 53—124)

This invention relates to a closing machine for cartons, and more particularly to an improved machine of this type which is especially adapted, in connection with cartons filled with produce, such as lettuce, and the like, to buttress all four of the side walls of the carton while causing the closure flaps of the carton to be moved to a closed position for sealing.

The subject apparatus constitutes an improvement over the apparatus disclosed in a commonly owned co-pending application, Serial Number 506,937, filed May 9, 1955. Both the apparatus disclosed in said co-pending application, and the improved apparatus forming the subject matter of the present application are adapted to be embodied in a field crop packing machine of the type which is employed to harvest and pack field produce, such as lettuce. The machine of said co-pending application operates to fold a pair of oppositely disposed side walls of a lettuce-filled carton against outward bulging as it moves the closure flaps of the carton to a closed position for sealing. It is now required that such lettuce-filled cartons have all four side walls thereof retained in against outward bulging when the closure flaps are closed for sealing.

The essential object of the present invention is to embody means in the machine of the co-pending application whereby said machine may be adapted to act on all four side walls, instead of merely two, during the carton closing operation.

Other objects and advantages of the invention will be apparent from the following description taken in conjunction with the drawings forming part of this specification, and in which:

Figure 1 is a view in perspective of the carton closing machine of the present invention, with one of the closure flap presser plates being shown in dotted outline to prevent masking of the machine parts disposed behind said presser plate;

Figure 2 is a view taken along lines 2—2 of Figure 1 of the right half of the machine;

Figure 3 is a view similar to that of Figure 2, but showing the carton side holding elements in operative position;

Figure 4 is a detail view taken along lines 4—4 of Figure 2;

Figure 5 is a detail view taken along lines 5—5 of Figure 2; and

Figure 6 is another detail view taken along lines 6—6 of Figure 3.

With immediate reference to Figure 1, the machine comprises a rectangular frame 10 having integral therewith legs 12, a pair of channel members 14 secured to frame 10 at oppositely disposed sides of the top thereof, a plurality of conveyor rollers 16, and pair of oppositely disposed carton closing assemblies indicated generally at 18 and 20.

The carton closing assembly 18 comprises a vertically disposed plate 22, a plate, a plate 24 having a hinge connection 26 with plate 22, cylindrical post members 28 fixedly secured to plate 22, said post members 28 extend-

2

ing into sleeve members 30 fixedly secured to frame 10 and being adjustably secured thereto, as by set screws 32. The plate 22 has also secured thereto a bar 34 which is provided at its lower end with means for pivotally mounting the lower end of a two-way acting hydraulic cylinder 36. The piston rod 38 of cylinder 36 is pivotally secured, as by pin 40 to an arm 42, said arm having a forked end 44 which is fixedly secured, as by welding, to plate 24.

The carton closing assembly 20 comprises plate 46 secured to posts 48 which are supported in sockets 50 attached to a transversely disposed plate member 52 forming part of a wheel supported carriage assembly which is supported on guide rails carried by frame 10 below conveyor roller 16. Plate 54 is provided with a hinge connection 56 with plate 46, and plate 54 has associated therewith, in the manner described for plate 24, the two-way acting hydraulic cylinder 58.

The machine, as thus far described, corresponds to the machine which is disclosed in further detail in the aforesaid co-pending application. As disclosed in said application, when a lettuce-filled carton is brought onto the roller conveyor 16, control means are actuated to cause a hydraulic cylinder to move the carriage supporting carton closing assembly 20 inwardly of frame 10 to cause plates 22 and 46 to press against oppositely disposed side walls of the carton, and at the same time the cylinders 36 and 58 are actuated to cause the plates 24 and 54 to pivot downwardly and press the closure flaps of the carton to a closed position.

The following elements have been added to the machine to convert it to a machine which will retain all four side walls of the lettuce-filled carton against outward bulging when the closure flap presser plates 24 and 54 are moved downwardly. Carton closing assembly 20 is provided with an arm 60 which upon endward movement of the carriage supporting the assembly is pivoted 90° to press against the end of the carton, as shown in Figure 3, and said assembly is further provided with another arm 62 which upon endward movement of the assembly to the carton engaging position is moved forwardly to be in a position to retain the other end wall of the carton against bulging, as also shown in Figure 3.

The arm 60 is secured to a shaft 64 which is journaled for rotation in sleeve member 66 secured to plate member 52 and within semi-sleeve 68 carried by stub arm 70 which is secured to plate 46. A set collar 72 (see Figure 4) attached to shaft 64 abuts the upper end of sleeve 66 and supports the shaft for rotation. Secured to the lower end of shaft 64 is a lever arm 74 which is pinned to a clevis 76. A second clevis 78 is pinned to a side arm 122 of lever arm 82, and the two clevises 76 and 78 are connected together by a rod 80 having threaded ends of opposite hand. Lever arm 82 is pivotally connected to a fixed arm 84 which is secured to the transverse plate member 52. Lever arm 82 is provided at its free end with a roller 86 which engages a track member 88 having a curved end 90. The track member 88 is secured to frame 10 for longitudinal positional adjustment, as by bolts 92 extending through elongated slots, not shown, formed in the track member. Tension springs 120 and 94 interconnect lever arm 82 and clevis 76, respectively, with frame 10.

When a lettuce-filled carton 96 is moved onto the conveyor 16 between plates 22 and 46 and when plate 46 is caused to be moved toward the carton in the manner described in detail in the aforesaid co-pending application, lever arm 82 is caused to swing in a counterclockwise direction, with reference to Figures 2 and 3, and the roller 86 moves up the curved end 90 of track member 88, thereby causing the clevis and rod arrangement 76—80 to impart clockwise rotation to lever arm 74 and swing

arm 60 into engagement with an end of the carton 96, as shown in Figure 3. When the carton closing assembly 20 is backed away from the carton after the latter has been sealed, the springs 92 and 94 cause the arm 60 and the lever control system therefor to move from the position Figure 3 to the position of Figure 2, in which position arm 60 does not interfere with the removal from the conveyor of the sealed carton.

The fact that the track member 88 is longitudinally adjustable and the further fact that the clevises 76 and 78 may be moved either closer together or farther apart by selective rotation of rod 80 renders the arm 60 and lever control system therefor capable of proper operation in the manner described regardless of the width of the particular carton being acted upon. Thus, by moving the track member 88 to the left, with reference to Figures 2 and 3, the arm 60 will be caused to have a 90° movement for a lesser distance of movement toward the carton of carton closing assembly 20. Such leftward adjustment of the track member adapts the machine to act upon cartons of greater width than carton 96. On the other hand, when track member 88 is adjusted to the right, the machine is adapted to act upon cartons having a lesser width than carton 96. Rod 80 is in each case adjusted in accordance with the positional adjustment of the track member.

Arm 62 is mounted in a slide way 98 which has an arm 100 integral therewith secured to plate 46. Arm 62 is provided with an actuating arm 102 having an elongated slot 104 at one end through which a pin 106 carried by arm 62 extends, with said arm 102 having a pin 108 at the other end thereof residing with a vertically elongated slot 110 formed in bracket member 112 fixedly secured to frame 10. The heads of pins 106 and 108 are of greater diameter than the width of the respective slots 104 and 110 associated therewith. Another arm 114 fixedly connected to plate 46 is pivotally connected at 116 to arm 102.

When the carton closing assembly 20 is moved from the position of Figure 5 to that of Figure 6, arm 62 is moved forwardly through slide way 98 to a retaining position with respect to the other end of carton 96. In order to prevent damage to the end wall of the carton, the arm 62 is provided with a rounded end 118. When the assembly 20 is withdrawn to the carton release position, arm 62 is caused to return to the position of Figure 5 where it is not in the way of the next carton to be moved onto the conveyor 16. Slot 104 adapts the essentially arcuate movement of arm 102 to the linear movement of arm 62, and slot 110 allows arm 102 to be pivotally swung while the pivotal point 116 is being linearly, or horizontally, moved.

What is claimed is:

1. In apparatus of the type described having a support frame adapted to receive and support a filled carton, a pair of oppositely and vertically disposed carton side pressure plates carried by said frame, at least one of said plates being attached to said frame for movement toward and away from the other of said plates, and means for moving said one plate; the combination therewith of first arm means connected to one end of said one plate adapted upon movement of said one plate toward the other of said plates to be swung into a right angled position with respect to said one plate to embrace an end of a filled carton supported by said frame, and second arm means connected to the other end of said one plate adapted upon movement of said one plate toward the other of said plates to be projected transversely of said frame to embrace the other end of a filled carton supported by said frame, whereby the side and end walls of said carton will be supported against undesired bulging while the closure flaps thereof are closed and secured closed.

2. In apparatus of the type described having a support frame adapted to receive and support a filled carton, a pair of oppositely and vertically disposed carton side pressure plates carried by said frame, at least one of said

plates being attached to said frame for movement toward and away from the other of said plates, and means for moving said one plate; the combination therewith of a first arm pivotally connected to one end of said plate, a second arm slidably connected to the other end of said one plate, said first arm being normally parallel to and in alignment with said one plate, said second arm being disposed at a right angle to said one plate and having its forward end substantially in alignment therewith, lever means mounted on said one plate in connected relation with said first arm and in engagement with said frame adapted upon movement of said one plate toward the other of said plates to pivot said first arm into a right angled position with respect to said one plate to embrace an end of a filled carton supported on said frame; and lever means mounted on said frame and having a connected relation with said one plate and said second arm adapted upon movement of said one plate toward the other of said plates to slide said second arm forwardly to embrace the other end of a filled carton supported by said frame.

3. The combination set forth in claim 2, said first mentioned lever means comprising an arm fixedly disposed in relation to said one plate, a lever having one end thereof pivotally connected to the end of said fixedly disposed arm and having at its other end a roller in engagement with a frame supported trackway having an arcuate end, a link having its ends pivotally connected to said lever and to a stub arm secured to said first arm, said roller being adapted to travel along said trackway and along the arcuate end thereof as said one plate is moved toward the other of said plates to cause said link to pivotally move said stub arm and said first arm, and spring means interconnecting said lever and said link with said frame adapted upon movement of said one plate away from the other of said plates to return said first arm to its normally parallel and aligned position with respect to said one plate, said second mentioned lever means comprising a lever arm having its upper end slidably and pivotally connected to said second arm, having its lower end slidably and pivotally connected to said frame, and having an intermediate pivotal connection with a stub arm secured to said one plate.

4. The combination set forth in claim 3 comprising, further, means for adjusting the degree of pivotal movement of said first arm for a given degree of movement of said one plate whereby said first arm may be pivoted into embracing relation with the ends of cartons of varying width when said one plate is moved into engagement with the sides of said cartons, said means comprising an adjustable connection between said frame and trackway permitting longitudinal movement of the latter with respect to the former, and means for varying the effective length of said link.

5. Carton handling apparatus comprising a support frame; a roller conveyor mounted thereon, a plate, means vertically positioning said plate with respect to said frame and adapting said plate for movement toward said conveyor to press against a side wall of a filled carton disposed thereon and for movement away from said conveyor, an arm mounted on said plate, normal thereto and adjacent one end thereof, for reciprocal longitudinal movement, means interconnecting said arm and said frame and actuated by movement of said plate adapted upon movement of said plate toward said frame to extend said arm across said conveyor to embrace an end wall of a filled carton on said conveyor and adapted upon movement of said plate away from said frame to withdraw said arm out of the path of movement of a carton on said conveyor.

6. Carton handling apparatus comprising a support frame, a roller conveyor mounted thereon, a plate, means vertically positioning said plate with respect to said frame and adapting said plate for movement toward said conveyor to press against a side wall of a filled carton disposed thereon and for movement away from said con-

veyor, an arm carried by said plate and disposed adjacent an end thereof, said arm being mounted for horizontal pivotal movement, means interconnecting said arm and said plate and being in contact with said frame at one point at least, said means being actuated by movement of said plate adapted upon movement of said plate toward said frame to swing said arm transversely of said conveyor to embrace an end wall of a filled carton on said conveyor and adapted upon movement of said plate away from said frame to swing said arm out of the path of movement of a carton on said conveyor.

7. Carton handling apparatus as set forth in claim 6, said last mentioned means embodying means for adjustment of the same to enable said arm to be swung transversely of said conveyor as the distance said plate moves is varied in accordance with variations in the width of cartons being handled.
